ATTORNEYS.

UNITED STATES PATENT OFFICE

ERIC SANDSTROM, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed March 10, 1931. Serial No. 521,443.

The present invention is directed to the improvement of wringers, particularly the mounting of the bearing blocks for the shafts for the lower rolls of wringers. The bearing blocks of most wringers are supported on some part of the side stile and where this support is out of alinement with the axis of the shaft frequently the bearing surface of the shaft on the bearing portion of the bearing block is very slight. One feature of the present invention is to so support the bearing block that it may accommodate itself to the shaft. Another feature of the invention is an improvement of the manner of supporting the bearing block, particularly in connection with wringers having sheet metal frames. Other features and details of the invention will appear from the specification and claims.

A preferred embodiment of the invention is illustrated in the accompanying drawing as follows:—

Fig. 1 shows a front elevation of the wringer, partly in section.

Fig. 2 an enlarged view of a stile and the bearing block and support therein.

Fig. 3 a perspective view of one of the bottom frame corners, parts being broken away to better show construction.

The wringer frame comprises a base 1 of channel shape, stiles 2 of box shape and a top bar 3. Wringer rolls 4, 4 are provided. The rolls have shafts 5, 5. A lower bearing block 6 and an upper bearing block 7 at each end are mounted in the stile and a spring 8 operates against the upper bearing block putting tension on the rolls. An adjusting screw 9 is provided for the spring 8.

Each side stile has an outer wall 10, side walls 11 and inturned lips 12 on their inner faces. The space between the lips forms a slot for the roll shafts. The channel-shaped base has the side flanges of the channel extending beyond the central web at its ends forming lips 13 which are arranged along the sides of the stiles at the bottoms of the stiles.

The stiles have the supporting lugs 14 struck up in them, the lugs extending inwardly. Openings in the stiles for forming these lugs are preferably covered by the lips 13, thus making the frame very slight. A

bearing support 15 is U-shaped, the lower ends resting on the lugs 15. The dimensions of the U-shaped plate approximate the inside dimensions of the stile so that the U-shaped plate is held in proper position by the walls 15 of the stile. The lower bearing 6 rests on the upper connecting portion of the U. This forms a simple structure which may be very readily assembled. The U-shaped supports are inserted into the stile from the top. The sides of the U-shaped support are initially slightly wider than the space between the side walls of the support so that there is a slight yielding engagement between the side walls of the support and the walls of the stile that retains the support in place after it is assembled.

While this manner of supplying the support for the bearing assures a uniformity of the supporting surface with regard to alinement with the axis of the lower roll shaft, there are sufficient production variations to interfere with the certainty of an equal bearing of the roll shaft throughout the bearing surface of the bearing block. To obviate this difficulty, I cut-away lower portion of the bearing block at 16 so that it rests only along the narrow end 17. It will readily be seen that the bearing block can rock on the narrow supporting portion 17 so as to permit the bearing portion of the block to assume an alinement with the axis of the roll and thus to present a complete bearing surface. The bearing block is made slightly narrower than the space between the outer wall and the lips 12 to permit of this rocking movement.

What I claim as new is:—

1. In a wringer, the combination of a frame comprising side stiles; a lower roll having an extending shaft; a bearing block; and a mounting for the block supported by the stiles, the block having a rocking engagement with the mounting.

2. In a wringer, the combination of a frame comprising sheet metal side stiles of box shape; a lower roll having a shaft extending into the box-shaped stiles; a bearing block mounted in the box-shaped stiles; and a mounting for the block supported within the

stiles, the block having a rocking engagement with the mounting.

3. In a wringer, the combination of a frame comprising box-shaped side stiles having inwardly extending shoulders therein; a lower roll having a shaft extending into the stiles; a bearing block for the shaft; and a mounting for the bearing block in the form of a U-shaped plate, the ends of the U resting on the shoulders.

4. In a wringer, the combination of a frame comprising box-shaped side stiles having inwardly extending shoulders therein; a lower roll having a shaft extending into the stiles; a bearing block for the shaft; and a mounting for the bearing block in the form of a U-shaped plate, the ends of the U resting on the shoulders, said bearing block having a rocking engagement with the mounting.

20 5. In a wringer, the combination of a frame comprising side stiles of box form the side walls thereof having slots and protruding lips under the slots, the lips providing depressions on the outer faces of the side stiles and a base having side extensions overlapping the sides of the stiles and covering the slots and depressions formed in the side stiles; a lower roll having a shaft extending into the stiles; a bearing block in the stiles; and a mounting 25 for the bearing block resting on the lips.

6. In a wringer, the combination of a frame comprising box-shaped side stiles having inwardly extending shoulders therein; a lower roll having a shaft extending into the stiles; a bearing block for the shaft; and a mounting for the bearing block in the form of a U-shaped plate, the ends of the U resting on the shoulders, the ends of the U-shaped plate being compressed by the walls of the stiles 30 holding the plate in place therein.

In testimony whereof I have hereunto set my hand.

ERIC SANDSTROM.
